M. TOWER.

Machine for Making Augers.

No. 41,822.

Patented March 1, 1864.

M. Tower

UNITED STATES PATENT OFFICE.

MARY TOWER, OF ROCHESTER, NEW YORK, ADMINISTRATRIX OF THE ESTATE OF ISIAH TOWER, DECEASED.

IMPROVEMENT IN MACHINES FOR MAKING AUGERS.

Specification forming part of Letters Patent No. 41,822, dated March 1, 1864.

To all whom it may concern:

Be it known that ISIAH TOWER, of the city of Rochester, county of Monroe, and State of New York, did invent a new and useful Machine for Twisting Augers; and I do hereby declare that the following is a full, clear, and exact description of the construction and operation of the same, reference being had to the annexed drawings, making a part of this specification, in which—

Figure 1 is a perspective view of the machine when in position to receive the plate to be twisted. Fig. 2 is an elevation of a pair of plates in the position when the auger is twisted. Fig. 3 is an elevation of a single plate. Fig. 4 is a plan of a pair of plates in the position when the auger is twisted. Fig. 5 is a plan of a single plate.

The nature of this invention consists in making a series of steel plates in pairs, and then placing one pair top of the other on a platform to the required height, these plates being shaped in the center to form a die, and then a cover put on, bolted with strong bolts to the platform. These plates are so arranged that by turning them the upper pair turns one-eighth around, when it catches the next pair, and that pair, going one-eighth around, catches the next, and so on until all are turned, and a flat piece or bar of steel or iron, of which to make an auger, being heated and put in between them, and the plates turned, the iron is twisted perfectly even and true. Then by changing the relative position of each plate to its mate by moving the upper one back into a certain position, the auger or twisted plate will of itself drop out of the machine.

To enable others skilled in the art to make and use this invention, I will proceed to describe its construction and operation by referring to the annexed drawings and letters of reference marked thereon.

A, Fig. 1, shows an iron platform on which the plates rest, and to which the lower plate is made fast.

B, Fig. 1, shows an iron cover or top to the machine.

The parts marked C, Fig. 1, show strong iron bolts, which hold the platform and cover together, and thereby keep the plates in position.

The parts marked D, Fig. 1, show nibs which

form a part of the upper plate of the series, and by which the plates are moved by means of a lever.

The parts marked E, Fig. 1, show blocks that form a part of the plates.

The parts marked F, Fig. 1, are a part of the blocks marked E, Fig. 1.

G, Fig. 2, shows the edge of an upper plate of a pair. H, Fig. 2, shows the edge of an under plate of a pair.

The parts marked E, Fig. 2, are blocks forming a part of the plate G, and are the same as the blocks marked E, Fig. 1.

The parts marked F, Fig. 2, show a part of the block E, Fig. 2, and are the same as the blocks marked F, Fig. 1.

The parts marked K, Fig. 2, are blocks on the lower plate, H, Fig. 2, and correspond with the blocks on the upper plate, (marked E, Fig. 2.)

The parts marked L, Fig. 2, show blocks which form a part of the blocks K, Fig. 2, and which correspond with the blocks, F, Fig. 2.

M M, Fig. 3, show pieces which form a part of the plate, but are raised on it, and are shaped so as to form a die, and give the required twist to the auger.

G, Fig. 4, shows the top of the plate G, Fig. 2.

The parts marked E, Fig. 4, show the tops of the blocks marked E, Fig. 2.

The parts marked F, Fig. 4, show the tops of the blocks marked F, Fig. 2.

The parts marked K, Fig. 4, show the tops of the blocks marked K, Fig. 2.

The parts marked L, Fig. 4, show the tops of the blocks marked L, Fig. 2.

M M, Fig. 4, show pieces which are raised on the lower plate, the sides of which are shown M M, Fig. 3.

The parts marked T, Fig. 4, show the pieces M M, Fig. 4, and M M, Fig. 3, cut to form a die to give the required twist to the auger.

U U, Fig. 4, show grooves cut in the upper plate to admit the rim or lip on the auger.

M M, Fig. 5, show the top of the pieces M M, Fig. 4, and M M, Fig. 3.

Now, it will be seen that by taking a flat piece of iron or steel, prepared for an auger, and finished complete, except the twist and, point, and by heating it, and then putting it into the top of the machine at W, Fig. 1, and, by means of a lever, turning the upper plate in

the direction shown by the arrows on Fig. 1, when the upper plate has moved one-eighth around, the block E on the upper plate strikes the block F on the next lower plate, and at the same time the block F on the lower plate, strikes the block E on the next upper plate below, which carries them one-eighth around, when the blocks on these plates strike the blocks on the next lower plate, and so on, until all the plates are turned, and, each plate being so shaped in the center as to give its required portion of twist to the auger, the auger must be twisted perfectly true. After this is done, by changing the relative position of one plate to the other of the pairs, by moving the upper plates back, so that the block E on Fig. 4, on the upper plate, will come against the block K, Fig. 4, on the lower plate, the center or die is opened, so that the twisted auger will of itself run down through the machine and out at the bottom.

The advantages of this machine are, first, that the auger must necessarily be perfectly

true, and therefore better than one made in the ordinary way; second, the augers can be finished up in a flat bar before being twisted, and thereby save a good deal of labor; third, augers can be made a great deal quicker than in the ordinary way, and for that reason made cheaper; fourth, any reasonable length of auger can be twisted perfectly true and straight, as the machine may be increased or decreased at pleasure, by adding or removing plates.

Having thus described the construction and operation of this invention, what I claim as new, and desire to secure by Letters Patent, is—

A series of plates constructed and operating in the manner and for the purpose substantially, as herein described and represented.

MARY TOWER.
